UNITED STATES PATENT OFFICE.

HENRY CHARLES WHITE, OF PHILADELPHIA, PENNSYLVANIA, ASSIGNOR
TO THOMAS DEVELON, JR., OF PHILADELPHIA, PENNSYLVANIA.

DESIGN FOR A RUG.

No. 38,398.

Specification for Design.

Patented Jan. 1, 1907.

Application filed November 28, 1906. Serial No. 345,576. Term of patent 3½ years.

To all whom it may concern:

Be it known that I, HENRY CHARLES WHITE, a subject of the King of Great Britain, residing in the city of Philadelphia, State of Pennsylvania, have invented a certain new, original, and ornamental Design for a Rug, of which the following is a specification, reference being had to the accompanying drawing, forming a part thereof.

In said drawing is shown a plan view of one half of the design, the other half (not shown) being a duplicate thereof.

I claim—

The ornamental design for a rug, as shown.
HENRY CHARLES WHITE.
